SAMUEL S. BURT, OF MARQUETTE, MICHIGAN.

Letters Patent No. 65,540, dated June 11, 1867.

IMPROVED RAILWAY CHAIR.

The Schedule referred to in these Letters Patent and making part of the same.

TO ALL WHOM IT MAY CONCERN:

Be it known that I, SAMUEL S. BURT, of Marquette, county of Marquette, State of Michigan have invented a new and useful Railroad Rail Chair; and hereby declare the following to be a full, clear, and exact description thereof, reference being had to the accompanying drawings making part of this specification, in which—

Figure 1 is a longitudinal section taken vertically through the centre of my improved rail and chair.

Figure 2 is a transverse section taken vertically through the rail and its chair.

Figure 3 are end views of the rail and rail chairs in detail.

Similar letters of reference indicate corresponding parts in the several figures.

The object of this invention is to prevent railroad rail sections from working loose and becoming battered down in consequence of the concussions and strain upon the rails caused by passing and repassing trains over the rail joints. My invention is designed to provide for the use of a reversible H rail of a peculiar form, and for supporting such rail by means of a three-part chair, in such manner that while the base, web, and lips of the rail are all firmly embraced and supported by the chair, the chair itself is prevented from becoming loose or straining the spikes which confine it down upon the cross-tie.

The nature of my invention consists in supporting the rail-base and sustaining it against lateral thrust, by seating it in a recess which is formed partly in the chair-base, and partly in plates which are secured on the sides of the rail and which support the web and head, so that the lateral as well as vertical pressure upon the rail will be resisted by the solid metal of the chair, as will be hereinafter described. It also consists in seating the side supporting plates upon the rail-base, and into the chair-base, in such manner that the latter shall serve as a vertical support, and also a lateral support for the rail, and prevent the working loose or straining of the spikes which hold the rail and chair upon the cross-tie, as will be hereinafter described. It also consists in seating the rail-base and the bases of its side supporting plates within recesses which are formed in the chair-base, in such manner that the spikes which hold the rail and chair upon the cross-tie shall pass through the said side plates and chair-base, and between outer and inner supporting lips upon the latter, and prevent an upward tendency of the side plates, as will be hereinafter described.

To enable others skilled in the art to understand my invention, I will describe its construction and operation.

The rail which I have represented in the drawings, and for which my improved chair is especially adapted, is of an H form, and consists of two heads *a a*, of the same shape and size, and which have rounded lips terminating at their junction with the contracted web *b*, in plane faces *c c*, and bevelled faces *d d*, which latter increase the width of the web at those points requiring the greatest strength, and also serve another office which will be hereinafter described. This rail it will be seen is reversible; that is to say, when one exposed surface becomes too much worn for use it may be turned over and used as long with the opposite side uppermost. The chair consists of three separate parts *A B B*, which are constructed of wrought iron pressed into proper shape by machinery suitably adapted to the purpose. The object of pressing or swaging the metal into the required forms is to have the grain of the metal of the chair transverse to the length of the rail, so as to afford greater strength and rigidity to the parts than could be obtained by having the grain of the metal run in any other direction. The chair-base *A* is constructed with a concave depression, *e*, extending longitudinally through its centre, which depression corresponds in shape and size to the rail-heads, and forms a seat for receiving either of said heads. The object of this seat is to prevent any lateral movement of the base of the rail, and to afford a firm base and side support for the rail-base, so that it shall not be battered or injured at the ends of the rail sections. On both sides of this central seat *e*, longitudinal channels *f f* are formed, which have on each side of them elevations *g g* and *h h*, and form receptacles for receiving the bases of the side supporting plates *B B*, as shown in figs. 2 and 3. The elevations *g g*, on the outer edges of the chair-base *A*, form abutments for the corresponding edges of the plates *B B*, so as to assist in resisting lateral pressure upon these plates, and also to prevent the outward thrust thereof. The intermediate elevations *h h* are produced in the act of forming the seat *e* for receiving the rail-base, and they have their upper ends terminated in flat surfaces *i i*, which are in a plane parallel to the bottom surfaces of the channels *f f* and flat shoulders *c c* of the rail-heads, as shown in fig. 2. The outer sides of said elevations incline outward so as to allow the plates *B B* to be contracted as much as possible, and their bases brought near the vertical centre of the rail. The said supporting plates *B B* are con-

structed with horizontal surfaces $c'c'$, $i'i'$, and $f'f'$, corresponding to their respective surfaces $c c$, $i i$, and $f f$ of the rail and its chair-base, as shown in figs. 2 and 3. These plates B are also constructed with concave recesses $j j$ in them corresponding in form and size to those portions of the lips of the rail-base which are not protected by the seat e , so that all that portion of the rail which is below the shoulders $c c$ of its head is enclosed and tightly held by the chair. Those portions of the side plates B B which abut against the web of the rail are chamfered so as to fit snugly against the corresponding surfaces $d d$, and thus support the web at every point between the two rail-heads. It will be seen from the above description that the plates B B cannot be introduced into their places or removed therefrom, except by sliding them in a direction with the length of the rail. The bases of these plates cannot under any circumstances rise from their channels or seats in the chair-base, consequently there will be no tendency to draw the spikes D D which pass through the plates A B B, and secure the whole down upon the cross-ties. These plates B B not only afford lateral supports to the rail by their abutting against the elevations $g g$ upon the chair-base, but they also afford vertical supports for the lips of the rail by extending beneath these lips, and bearing upon horizontal surfaces or shoulders $c c$ and $i i$ of the rail and chair-base. With a rail which is seated in a recess formed in a chair-base, and having its base and the greater portion of its lips surrounded by the solid metal of said base, as I have shown, there will be no possibility of the depression of the ends of the rail sections. Such a solid support will effectually prevent the battering down or bending of the rail ends by car-wheels passing over them. By constructing the side plates B as described, so as to form receptacles for the upper portion of the rail-base, and to fit snugly over and upon the surfaces $c c$ thereof, the lips of the rail head or table will be prevented from injury, and those portions of the plates B which are between the rail lips will also be protected from strain or displacement by vertical pressure, and those portions of the plates B which extend outward and downward from diagonal braces and supports for staying the rail against lateral thrust or strain. One of the greatest difficulties which has attended sectional railroad chairs hitherto made, has been the working loose of the spikes which secured the chairs to the cross-ties. This difficulty is removed by constructing the chair sections A B B as above described, so that the chair-base A will firmly hold the sections B B down in place, even if the spikes should not be inserted through them, as I have shown.

I am aware that reversible H rails, approaching the form of the rail which I have herein described, have been seated into recesses formed in chair plates, and that, in conjunction with such recesses, diagonal braces have been used for preventing the rails from tilting laterally. Such braces do not support the lips of the rails against downward pressure, nor are they self-holding. I do not therefore lay claim broadly to the seating of rails into depressions, nor the supporting of the rails by diagonal braces. I am also aware that a railroad rail chair has been constructed of one piece of metal with lip and base supports, and therefore I lay no claim to such a chair.

Having described my invention, what I claim as new, and desire to secure by Letters Patent, is—

1. A three-part railroad chair which is adapted for a reversible H rail, and so constructed that the base of the rail will be received and closely held partly by a recess, e , in the chair-base, and partly by recesses $j j$, the side supports B, substantially as described.
2. In combination with a double-headed rail constructed with flat shoulders at $c c$, I claim a three-part chair A B B, with the lower head or base of the rail fitted into a recess, e , in the chair-base A, and the lips of both rail-heads sustained by the upper portions $c'c'$ of the side plates B B, substantially as described.
